(57) **CLAIM**

The ornamental design for a headphone cover, as shown and described.

DESCRIPTION

FIG. 1 is a perspective view of a headphone cover, showing my design, the left and right headphone covers are mirror images of each other;

FIG. 2 is a right-side view of the left headphone cover of FIG. 1;

FIG. 3 is a front view of the left headphone cover of FIG. 1; FIG. 4 is a left-side view of the left headphone cover of FIG. 1;

FIG. 5 is a rear view of the left headphone cover of FIG. 1; FIG. 6 is a top view of the left headphone cover of FIG. 1; FIG. 7 is a bottom view of the left headphone cover of FIG. 1; FIG. 8 is a front view of a second embodiment of a headphone cover having a right side view as shown in FIG. 2, a left side view as shown in FIG. 4, a top view as shown in FIG. 6 and a bottom view as shown in FIG. 7;

FIG. 9 is a rear view of the headphone cover of FIG. 8;

FIG. 10 is a perspective view of a third embodiment of a headphone cover, the left and right headphone covers are mirror images of each other;

FIG. 11 is a right-side view of the left headphone cover of FIG. 10;
FIG. 12 is a front view of the left headphone cover of FIG. 10;
FIG. 13 is a left-side view of the left headphone cover of FIG. 10;
FIG. 14 is a rear view of the left headphone cover of FIG. 10;
FIG. 15 is a top view of the left headphone cover of FIG. 10;
FIG. 16 is a bottom view of the left headphone cover of FIG. 10;
FIG. 17 is a front view of a fourth embodiment of the headphone cover having a right side view shown in FIG. 11, a left side view as shown in FIG. 13, a top view as shown in FIG. 15 and a bottom view as shown in FIG. 16;
FIG. 18 is a rear view of the headphone cover of FIG. 17;
FIG. 19 is a perspective view of a fifth embodiment of a headphone cover, the left and right headphone covers are mirror images of each other;
FIG. 20 is a right-side view of the left headphone cover of FIG. 19;
FIG. 21 is a front view of the left headphone cover of FIG. 19;
FIG. 22 is a left-side view of the left headphone cover of FIG. 19;
FIG. 23 is a rear view of the left headphone cover of FIG. 19;
FIG. 24 is a top view of the left headphone cover of FIG. 19;
FIG. 25 is a bottom view of the left headphone cover of FIG. 19;

FIG. 26 is a front view of a sixth embodiment of a headphone cover having a right side view as shown in FIG. 20, a left side view as shown in FIG. 22, a top view as shown in FIG. 24 and a bottom view as shown in FIG. 25;
FIG. 27 is a rear view of the headphone cover of FIG. 26;
FIG. 28 is a perspective view of a seventh embodiment of a headphone cover, the left and right headphone covers are mirror images of each other;
FIG. 29 is a right-side view of the left headphone cover of FIG. 28;
FIG. 30 is a front view of the left headphone cover of FIG. 28;
FIG. 31 is a left-side view of the left headphone cover of FIG. 28;
FIG. 32 is a rear view of the left headphone cover of FIG. 28;
FIG. 33 is a top view of the left headphone cover of FIG. 28;
FIG. 34 is a bottom view of the left headphone cover of FIG. 28;
FIG. 35 is a front view of a eighth embodiment of a headphone cover having a right side view as shown in FIG. 29, a left side view as shown in FIG. 31, a top view as shown in FIG. 33 and a bottom view as shown in FIG. 34; and,
FIG. 36 is a rear view of the headphone cover of FIG. 35.
The broken lines form no part of the claimed design.
